CLAMP

Elias J. Hornung, Rochester, N. Y.

Application February 26, 1934, Serial No. 712,958

11 Claims. (Cl. 24—19)

This invention relates to clamps and more particularly to hose clamps.

In a hose clamp particularly of the type employed in the cooling systems of gas engines, it is essential that the clamp be of such construction that it can be readily applied or removed from the hose coupling and at the same time it must be of a design that can be readily manufactured from a minimum amount of material 10 preferably on an automatic machine.

The clamp of the present invention satisfies these requirements and in addition is sturdy and durable.

The various features of the invention will appear from the detailed description and claims when taken with the drawing in which Fig. 1 is a perspective view of a preferred form of clamp; Fig. 2 is a perspective view of a slightly different form of clamp; Fig. 3 is a perspective view of a modified form of clamp, and Fig. 3a is a fragmentary sectional view thereof taken substantially on the line 3—3 of Fig. 3; Fig. 4 is a perspective view of an additional modified form of clamp, and Fig. 4a is a fragmentary sectional view thereof taken substantially on the line 4—4 of Fig. 4; Fig. 5 is a perspective view of another modified form of clamp; and Fig. 6 is a perspective view of a still further modified form of clamp.

Referring especially to Fig. 1, 5 designates a strip having therein one large central aperture and two small lateral apertures, and 6 designates a strip similar in shape to strip 5 and having similar apertures therein, except that its central aperture is threaded. A piece of wire 7 has one of its ends 8 extending through a lateral aperture in the strip 5 and then clinched back upon itself, while the other end 9 of this piece likewise extends through a corresponding aperture in the strip 6 where it is clinched upon itself. 40 A second piece of wire 10 has its free ends similarly extending through the other lateral apertures of the strips 5 and 6 where these ends are clinched upon themselves in a manner similar to the ends 8 and 9 of the piece 7. A bolt 11 passes through the central aperture in the strip 5 and makes threaded engagement with the central threaded aperture in the strip 6 so that these strips can be drawn together or separated to tighten or loosen the clamp as desired. In order 50 to bridge the space between the strip 5 and 6, a single loop of wire 12 has its free ends attached to the strip 6 and has its looped end extending between the wires 7 and 8 adjacent strip 5. The fastening of the loop 12 to the strip 6 is effected 55 by wrapping the part 13 of the loop about this

strip with the end portion of the wire being clinched against one face of the mentioned strip. Similarly the other end portion of the wire of the loop 12 has a part 15 wrapped about the strip 6 with the extreme end portion 16 of the wire clinched against one face of the strip. In this manner the loop 12 is securely fastened to the strip 6.

In the form of clamp shown in Fig. 2 there are two metal strips 20 and 21 each having therein two lateral apertures and a large central aperture of which the central aperture in the strip 21 is threaded. A piece of wire 22 of arcuate form has one free end 23 extending through a lateral aperture in the strip 20 where it is clinched upon itself. The other end of this wire, as indicated at 24, extends through a lateral aperture in the strip 21 and after being looped about a portion of this strip extends as part 25 having its free end 26 projecting into the space between the wires 22 and 27 adjacent the strip 20. A second piece of wire 27 identical in shape and arrangement with the wire 22, has one free end 28 extending through the other lateral aperture of the strip 20 where it is clinched back upon itself. The other free end of the wire 27 after it is looped about a portion of the strip at 29, then extends as a part 30 to bridge the gap between the strips 20 and 21. Wire 30 has its free end 32 extending into the space between the wires 22 and 27 adjacent its strip 20. Thus this form of clamp includes but two pieces of wire.

In the modified form of the invention shown in Figs. 3 and 3a, there are provided two notched or apertured metal strips 35 and 36 wherein the notches in the strip 35 extend along its edges while in the strip 36 the notches are provided only in the ends thereof. The strips 35 and 36 each has a central aperture therein of which the aperture in the strip 36 is threaded. A loop of wire 40 bridges the gap between the strips 35 and 36 and has its free ends 41 and 42 wrapped around a central stud 43 in the strip 35 which stud is formed by the mentioned notches. A single piece of wire intermediate of its ends is wrapped about the ends 41 and 42 of the loop 40 in the mentioned notches in strip 35 and is then bent into arcuate form as indicated at 44 and 45. The free end 46 of piece 44 is inserted into the end notch in the strip 36 and the material at this end of this strip is then compressed to grip the portion of wire adjacent its upset end 46. The end portion of the arcuate part 45 of the wire engages an end notch

in the strip 36, being gripped therein adjacent the upset free end 47 of the wire. Preferably the upset ends 46 and 47 are sharply bent at right angles to engage the edge of the strip 36. A bolt 5 39 passing through the central aperture in the strip 35 makes threaded engagement with the central threaded aperture in the strip 36 so that the clamp can be loosened or tightened at will.

The modified form of the invention shown in 10 Figs. 4 and 4a is identical in construction with the form of clamp shown in Fig. 3, except that the end portions 46 and 47 of the arcuate portions 44 and 45 of the wire extend through lateral apertures in the piece 36a and are there clinched 15 upon themselves, instead of being fastened in the end notches or apertures of piece 36 as shown in Fig. 3. To facilitate the understanding of the construction of this form of clamp the corresponding parts thereof are designated by the 20 same reference characters as were used in connection with corresponding parts of the clamp disclosed in Figs. 3 and 3a.

In the form of the invention shown in Fig. 5, a 25 strip 50 having a centrally apertured upstanding part and an angular portion 51, is provided. The clamp also includes a strip 52 having a lateral notch and end notches or apertures therein as well as a central threaded aperture. A single 30 piece of wire bent intermediate of its ends as indicated at 55 to engage the notches in the strip 52, is then shaped to form the arcuate parts 54 and 56. The free end of the wire part 54 extends through a lateral opening in the angular portion 51, and is then bent back upon itself at 53 to grip 35 one surface of the portion 51. The arcuate wire part 56 similarly extends through a lateral opening in the angular portion 51 and is then bent back upon itself at 57 to grip one surface of this portion. A second piece of wire 58 is formed into 40 a loop to bridge the space between the strips 50 and 52 with its free end extending between the wire parts 54 and 56 adjacent the strip 52. The ends of the wire 58 are attached to the strip 50 by being inserted through lateral openings therein 45 and being then bent back upon themselves as indicated at 59 and 60 to grip the surface of the portion 51.

In the form of the invention shown in Fig. 6, a 50 metal strip 65 having an upstanding part with a central aperture therein and an angular portion 66, is provided. A second metal strip 67 having a central threaded aperture therein and having a lateral notch and end notches or apertures 55 therein, is also provided. In this form of clamp but a single piece of wire is employed. This piece of wire is bent intermediate of its ends, as indicated at 73 to engage the notches in the strip 67. Thereafter, the parts of this wire are shaped into 60 arcuate form as indicated at 68 and 69. The wire part 68 after being inserted in a lateral opening in the angular portion 66, is wrapped around the edge of this portion to extend as a bridge 71 between the strips 65 and 67, the free end 70 of this bridge extending between the portions 68 and 69 adjacent the strip 67. Similarly, the wire part 69 extends through a lateral opening in the angular portion 66 and is wrapped around an edge of this portion to extend as indicated at 74 as a bridge across the space between 65 the strip 65 and 67 having its free end 75 extending into the space between the parts 68 and 69 adjacent the strip 67.

From the foregoing disclosure it will be seen 70 that the clamp of this invention is sturdy in con-

struction and is simple and economical to manufacture.

What I claim is:

1. In a clamp, two strips having apertures 5 therein, arcuate portions of wire connecting said strips and having their end portions respectively engaging the walls of said apertures, wire portions carried by one strip and projecting adjacent the other strip, and means for adjusting said strips toward and away from each other.

2. In a clamp, two spaced strips having apertures therein, spaced arcuate portions of wire connecting said strips and having their end portions respectively engaging the walls of said apertures, wire portions carried by one strip and projecting adjacent the other strip to bridge the space between said strips, and means for adjusting said strips toward and away from each other.

3. In a clamp, two spaced strips having apertures therein, two arcuate pieces of wire having 20 their ends respectively attached in the apertures in said strips, wire portions bridging the space between said strips, and means for adjusting said strips toward and away from each other.

4. In a clamp, two spaced strips having apertures therein, a single piece of wire formed into 25 two arcuate parts engaging the walls of the apertures in said strips, portions of said wire bridging the space between said strips, and means for adjusting said strips toward and away from each other.

5. In a clamp, two strips, one of which is notched at its edges, a piece of wire bent intermediate of its ends to engage the notches in said strip, arcuate portions of said wire attached to 25 said other strip, and means for adjusting said strips toward and away from each other.

6. In a clamp, two strips, one which is notched at certain of its edges, a piece of wire bent intermediate of its ends to engage the notches in said 40 strip, arcuate portions of said wire attached to said other strip, wire portions engaging one of said strips and projecting toward said other strip to bridge the space between said strips, and means for adjusting said strips toward and 45 away from each other.

7. In a clamp, two spaced strips, one of which is notched at certain of its edges, a piece of wire bent intermediate of its ends to engage the notches in said strip, arcuate portions of said wire 50 attached to said other strip a portion of said wire engaging one of said strips to bridge the space therebetween, and means for adjusting said strips toward and away from each other.

8. In a clamp, two strips, one of which is notched at certain of its edges, a piece of wire bent intermediate of its ends to engage the notches in said strip, arcuate portions of said wire attached to said other strip, portions of said wire 55 engaging said last-mentioned strip and projecting toward said notched strip to bridge the space between said strips, and means for adjusting said strips toward and away from each other.

9. In a clamp, two strips, arcuate portions of 65 wire connecting said strips, a loop of wire having its ends wrapped around one of said strips, the free end of said loop projecting adjacent the other strip to bridge the space between said strips, and means for adjusting said strips toward and 70 away from each other.

10. In a clamp, two strips, two arcuate pieces of wire connecting said strips, a loop of wire having its ends wrapped around one of said strips, the free end of said loop projecting adjacent 75

the other strip to bridge the space between said strips, and means for adjusting said strips toward and away from each other.

11. In a clamp, two spaced strips, one of which is provided with a notch in at least one of its edges, two arcuate portions of wire having ends

attached to one strip and other ends fastened in the notch in said other strip, wire portions bridging the space between said strips, and means for adjusting said strips toward and away from each other.

ELIAS J. HORNUNG.
